UNITED STATES PATENT OFFICE.

WILLIAM HAWKS, OF MIDLAND, MICHIGAN.

DESIGN FOR A GENERATOR FOR HYDROCARBON-LAMPS.

SPECIFICATION forming part of Design No. 31,032, dated June 20, 1899.

Application filed May 13, 1899. Serial No. 716,746. Term of patent 7 years.

To all whom it may concern:

Be it known that I, WILLIAM HAWKS, a citizen of the United States, residing at Midland, in the county of Midland and State of Michigan, have invented and produced a new and original Design for Generators for Hydrocarbon-Lamps, of which the following is a specification, reference being had to the drawing forming a part thereof.

10 The figure is a side elevation of a generator embodying the features of my invention.

As shown in the drawing, the leading or material feature of my design consists in the form or configuration of a generator wherein

15 A is the tubular body portion, having the enlarged upper part A' and the annular flange

A² at its lower end. The bosses A³ and A⁴ extend radially from diametrically opposite sides of the body portion A, while an L-shaped arm A⁵ projects downward from the lower face 20 of the annular flange A². The outer end of the arm A⁵ has the depending stem A⁶, screw-threaded internally and externally and bearing the enlarged portion B at its lower end.

I claim as my invention—

25 The design for a generator for hydrocarbon-lamps, substantially as herein shown and described.

WILLIAM HAWKS.
